(57) **CLAIM**

The ornamental design for a device mounting stand, as shown and described.

DESCRIPTION

FIG. 1 is a perspective view of a device mounting stand showing a supported device in environment;

FIG. 2 is another perspective view of the device mounting stand of FIG. 1;

FIG. 3 is a left side view of the device mounting stand of FIG. 1;

FIG. 4 is a right side view of the device mounting stand of FIG. 1;

FIG. 5 is a front view of the device mounting stand of FIG. 1; and,

FIG. 6 is a rear view of the device mounting stand of FIG. 1. The broken lines in the drawing indicate environmental structure and form no part of the design to be patented.
